UNITED STATES PATENT OFFICE.

EDWARD FALES, OF BOSTON, MASSACHUSETTS.

STEAM-BOILER.

SPECIFICATION forming part of Letters Patent No. 442,967, dated December 16, 1890.

Application filed August 27, 1890. Serial No. 363,176. (No model.)

To all whom it may concern:

Be it known that I, EDWARD FALES, a citizen of the United States, residing at Boston, in the county of Suffolk and State of Massachusetts, have invented new and useful Improvements in Steam-Boilers; and I do hereby declare the following to be a full, clear, and exact description of said invention, reference being had to the accompanying drawings, and to the letters of reference marked thereon, which form a part of this specification.

My invention relates to improvements in devices for generating steam.

The object of my invention is to provide a device which will generate steam and superheat the same with much less fuel and in a shorter period of time than has heretofore been accomplished.

My invention consists in providing the rear portion of the furnace with an adjustable damper or draft-regulator and with a series of removable teeth or grate-bars to hold the fuel in position while the damper is being raised or lowered.

My invention consists, further, in connecting the water chambers or compartments in which the steam is generated with a steam dome or drum, said dome or drum being arranged so that it will receive a portion of the waste heat from the furnace and also the radiated heat from the water-chamber. Other novel features will be described, and pointed out in the claims.

This invention is designed as an improvement on the devices shown and described and claimed in my application filed June 24, 1890, Serial No. 356,571, and in which the main features of my invention are claimed.

Referring to the accompanying drawings, Figure 1 is a perspective view of my device. Fig. 2 is a longitudinal sectional view. Fig. 3 is a top or plan view. Fig. 4 is an end view. Fig. 5 is a vertical sectional view. Fig. 6 is a sectional view on line xx of Fig. 2. Fig. 7 is a sectional view on the line yy of Fig. 2. Fig. 8 is a sectional view showing the damper or draft-regulator and also one removable grate-bar. Fig. 9 is a detached view of one of the bars. Fig. 10 is a detached view of one of the frames of the generator and the shoes used in supporting the same.

A indicates the furnace, which is set in a

suitable housing of brick-work or masonry, and is by preference of the form shown in the patents granted to me November 19, 1890, Nos. 415,626 and 415,627, in which the fuel is fed to the point of combustion by gravity, and said fuel being supported, together with the incandescent fuel which is being burned, on a bed of ashes, the fuel being fed down by gravity, as before stated, to the point where it is consumed by removing a portion of the ashes from the lower part of the furnace or from the bottom of the ash-pit, and in the patents above named the draft is regulated by a register in the front door or by the opening of said door slightly. In the present instance I provide the rear end of the furnace with a slide-door or damper B, which is raised and lowered by means of the screw-threaded shaft C and hand-lever D, as clearly shown in Fig. 2, and by which means the throat where the products of combustion pass through to the water-chambers is enlarged or contracted, as may be desired. The rear wall of the furnace is also provided with a series of loops or supports E to receive the movable grates or teeth F, said teeth or bars being made of suitable refractory material, such as fire-clay or plumbago, and the object of which is to prevent the fuel from falling forward into the throat of the furnace when the damper is raised.

At the bottom of and to the rear of the furnace is provided a gutter G, which communicates with the outer air through the door H and through which the ashes are removed. As, for instance, as the fuel is to be let down to the point of combustion the attendant simply pushes the ashes back from the bottom into the gutter G, and the incandescent fuel, together with the green fuel, will be lowered to the point of combustion and the ashes withdrawn from the gutter through the door.

I is the throat leading from the furnace to the water-chambers, where the steam is generated. The generator is composed of the hollow base K, of any suitable size and dimensions, which communicates with the hollow columns or chambers L. The columns or chambers L are connected together by horizontal chamber M, and between the hollow columns or chambers L are arranged a series of thin or narrow water-chambers N, the lower

ends of which communicate with the base K while the upper ends of said chambers extend upward nearly to the horizontal chamber M. There may be any desired number of these 5 water-chambers N arranged in a line parallel with the exit-line of the products of combustion, and in the construction of these steam-generating chambers I use a bar or bent O, as indicated in Fig. 10, which rests in the 10 shoes P, said shoes being firmly riveted to the upper walls of the chamber K.

The shoes P, which are necessary to make this construction of boiler a practical one, are for the purpose of making a strong steam-tight connection between the several chambers of the boiler and especially at the corners, where a proper joining of the walls of the chambers cannot be accomplished by other forms of construction, and hence the 15 shoe P forms an indispensable feature of the boiler.

The metal plates which connect the outer walls of the generating-chambers N are riveted to the bars O, so as to form a complete 20 structure, as shown in Fig. 4.

R is a steam dome or superheater, which is supported in any suitable manner above the water-chamber M and between the walls of the water-chambers L, the upper portions of 25 the water-chambers L being connected so as to communicate with the steam-drum R by means of the pipes S S. The steam-drum or superheater R is provided with the pipe T, which conveys the steam to any suitable point 30 for use.

The upper portions of the generating-chambers M and N are connected to and communicate with the upper portions of the chambers L by means of the pipes U, which are primarily 35 designed to permit the air to escape from the upper portion of said chambers when the same are being filled with water and which will allow the said chambers to be always full, and in the generation of steam a certain portion 40 of the steam will be conducted through the pipes U to the upper portion of the chambers L, where it enters the superheater or chamber R; but the greater portion of the steam generated in the chambers N passes 45 down and enters the chambers L through its connection at the base.

Certain portions of the waste products of combustion pass off from the chamber M and surround the superheater or drum R, which, 50 together with the heat radiated from the chambers L and N, surround and superheat the steam in the chamber R, and thus make the furnace very effective. The waste products pass up around the chambers R and 55 pass out to the stack W through pipe A', while the products of combustion, which pass between the chambers N, are conducted to the stack W through the pipe B'.

The walls of the generating-chamber—that 60 is, the masonry-work—are provided with a flue which enters the generating-chamber at

each side and communicates with the pipes A' B', leading to the stack W. The object of this construction is to carry the waste products of combustion in a tortuous manner, so 65 as to allow the water-chambers to absorb the heat, as indicated by the arrows in Figs. 6 and 7.

It will be seen that the generating-chambers N are wider at the bottom, top, and ends 70 than they are at their central portions, as shown in Fig. 5, so as to insure a constant feed or flow to the central portion of the said chambers where the flame is the hottest.

C' indicates a supply-pipe, which feeds the 75 water into the chamber K, while D' indicates a return-pipe, through which the water of condensation is allowed to pass back into the chamber K when hot water or steam is used as a heating medium.

The generating-chambers K, L, M, and N are provided with suitable braces or stay-rods E', so as to give the same a rigid body, and in this way insure great strength by distributing equally upon all parts of the boiler 80 the strain of the steam-pressure.

What I claim is—

1. The furnace provided at its rear end with an adjustable damper or draft-regulator and also with a series of vertically-arranged 90 teeth or grate-bars, substantially as described, whereby the fuel is held in position when the damper is raised, as set forth.

2. In a device for generating steam and also for the circulation of hot water, the water or steam chambers arranged on each side of the combustion-flue or passage-way connected by a water or steam chamber to divide the flue or passage-way longitudinally, and a superheating-chamber communicating 105 with the water or steam chambers located between the water or steam chambers in the flue or passage-way, substantially as set forth.

3. In a device for generating steam and for circulating hot water, the vertically-arranged 110 steam-generating chambers, a water or steam chamber dividing the combustion flue or chamber horizontally, and flues at each side of the combustion-chamber at points above and below the horizontally-dividing chamber 115 and leading to the stack, substantially as set forth.

4. In a device for generating steam and for circulating hot water, the water or steam chambers arranged on each side of the combustion-flue or passage-way, a series of narrow water or steam chambers arranged both vertically and horizontally between the main water or steam chambers, and a series of pipes forming 120 communications between the narrow chambers and the main chambers, substantially as set forth.

5. In a steam-generator of the character described, the shoes for connecting the chambers with each other, substantially as set forth.

6. In a steam-generator of the character described, a bar or bent and the shoes riveted

thereto for securing the vertical and horizontal chambers to each other, substantially as set forth.

7. The method herein described of generating steam, which consists in passing a portion of the products of combustion from a suitable furnace through a chamber, the walls and partitions of which form steam-generating chambers which communicate with a superheater, and in passing the remaining por-

tion of the products of combustion around and in contact with the superheating-chamber, as set forth.

In testimony whereof I affix my signature in the presence of two subscribing witnesses.

EDWARD FALES.
